OF NEW YORK, N. Y., A FIRM.

HOISTING APPARATUS.

1,150,604.

Specification of Letters Patent.

Patented Aug. 17, 1915.

Application filed January 22, 1915. Serial No. 3,667.

To all whom it may concern:

Be it known that I, JOHN A. KEARNEY, a citizen of the United States, residing at Newark, in the county of Essex and State of New Jersey, have invented a certain new and useful Improvement in Hoisting Apparatus, of which the following is a specification.

The invention relates to hoisting machinery in which a tubular standard carrying the hoisting head is received telescopically in a hollow post, and is based on the apparatus shown and described in Letters Patent to me, dated June 23, 1914, No. 1,101,190, and the object of the invention is to provide simple, inexpensive means for raising and lowering the standard in the post, and for lessening the danger of accident in operating this portion of the hoisting apparatus.

The invention consists in certain novel features of construction and arrangement by which the above objects are attained, to be hereinafter described and claimed.

The accompanying drawings form a part of this specification and show the invention as it has been carried out in practice.

Figure 1 is a side elevation of the apparatus in the extended condition for service in hoisting a load. The remaining figures are on a larger scale. Fig. 2 is a side view of the elevating mechanism. Fig. 3 is a corresponding front elevation. Fig. 4 is a vertical section of the same, partly in elevation. Fig. 5 is a corresponding plan view, partly in horizontal section. Figs. 6, 7 and 8 are side views of portions of the elevating mechanism, partly in vertical section, showing several positions of such portions relatively to each other.

Similar letters of reference indicate the same parts in all the figures.

A is a hollow post shown as firmly set and supported in a cellar hoist-way below the street level, and B is a tubular standard in-closed telescopically in the post and arranged to be raised and lowered relatively thereto and correspondingly elevate the hoisting mechanism, mounted on the upper end of the standard, above the street level for service in hoisting a load, or to lower the hoisting mechanism into the hoist-way below when not in use.

On the post A is a clamp or two-part

yoke D D¹ secured in place by the transverse bolts D², carrying a shaft C⁴ in the lower portion, on one overhung end of which is a pinion C³ in mesh with a gear-wheel C² on a similar shaft C above. The latter carries a spur-wheel F keyed thereon between the cheeks D, D¹ of the clamp and is rotated by a crank C¹ applied upon the squared end C⁵ of the pinion-shaft C⁴. The post A is slotted vertically as at a to permit the spurs F¹ of the spur-wheel F to extend therethrough and engage the series of holes b in the tubular standard, serving with the spur-wheel as a rack by which the tubular standard may be raised or lowered relatively to the post. The spurs F¹ are preferably cylindrical with hemispherical ends, and the holes b are circular, of slightly larger diameter than the spurs, and are so located in vertical series as to permit the spurs to engage deeply therein and serve to hold the tubular standard against rotary movement in the post without requiring other guiding means.

It will be noted by referring to Figs. 4, 6, 7 and 8, that in all positions of the spur-wheel one or more spurs are always reliably engaged in one or more holes b; in Fig. 4 one tooth or spur extends into the standard at a right angle and is fully engaged; in Fig. 6 one spur is in strong engagement while the succeeding spur is partially engaged; in Fig. 7 two spurs are well engaged, and in Fig. 8 one spur is in strong engagement while the preceding spur is still partially engaged. By this means the standard may be raised or lowered reliably and the weight and expense of the usual rack and pinion greatly reduced.

The hoisting mechanism at the upper end of the standard may be of any approved type, it is shown as a head K having laterally projecting parallel arms in which is mounted a shaft H carrying a gear-wheel H¹ in mesh with a pinion G¹ on a shaft G; the latter is equipped with a pawl G² and a suitable brake operated by the lever N, and is squared at one end to receive a crank L by which the pinion is turned and the drum H² rotated to wind the rope or cable P in raising the load M as will be understood. The head K is rotatably mounted in the upper end of the standard to permit the load to be swung and deposited upon the side-

walk, the standard being held against such rotation by the engagement of the spurs F^1 with the holes b .

In the patent above referred to the construction requires the standard to be slotted for a considerable portion of its length, thus weakening it and increasing the liability to distortion; the introduction and securing of a rack within the standard adds to the weight and to the cost of manufacture, and, as the interior surface of the commercial pipe used for the standard is frequently irregular, a further disadvantage is encountered in the difficulty of insuring perfect alinement of the rack. All these disadvantages are avoided by the employment of the spur-wheel in mesh with the series of perforations in the standard, and such construction is economical, strong, durable, and eminently reliable. On the upper transverse bolt D^2 is mounted a pawl J adapted to ride idly over the spurs when the spur-wheel F is rotated in the direction to elevate the standard and to fall by gravity and engage one of the spurs and thus hold the standard in the elevated position when the turning movement ceases and the desired elevation is attained. A lever or extension J^1 at the upper end of the pawl permits the latter to be raised and held out of contact with the spurs during the lowering movement of the standard, and in order to prevent disengagement of the pawl by grasping its lower end and thus endangering the hand of the operator, a shield D^3 in the form of a laterally projecting flange on the

part D^1 of the clamp, extends over the spur-wheel and lower portion of the pawl, effectually preventing access to these parts and eliminating all danger of accident due to the introduction of the fingers.

A^3 is a pin adapted to be thrust through suitable holes, not shown, in the post below the lower end of the standard when the latter is fully elevated and support it reliably during the hoisting operation.

I claim:—

In an apparatus of the character set forth, a hollow post, a tubular standard having a series of holes in alinement and arranged to slide within the post, the post having a vertical slot in alinement with the holes of the standard, a clamp on the post comprising a two-part yoke, a spur wheel and shaft therefor carried by said yoke, a gear wheel on said shaft, a pinion meshing with the gear wheel, a transverse bolt in said yoke, a pawl on said bolt, to engage between the spurs of the spur wheel, a lever at the upper end of said pawl, and a laterally-projecting flange on the clamp extended over the pawl and spur wheel and within the confines of the gear wheel to form a shield, the end of said lever projecting beyond the shield and movable in a space between the shield and post.

In testimony that I claim the invention above set forth I affix my signature, in presence of two witnesses.

JOHN A. KEARNEY.
